MUSICAL TIME INDICATOR

Lorenzo G. Fascinato, Canton, Mo.

Application November 29, 1932

Serial No. 644,884

5 Claims. (Cl. 58—130)

The present invention relates to new and useful improvements in musical time indicators and has for its primary object to provide, in a manner as hereinafter set forth, an instrument of this character embodying a novel construction, combination and arrangement of parts through the medium of which the various rhythm combinations may be obtained as desired simultaneously with the beat of the measure.

10 Other objects of the invention are to provide a musical time indicator of the character described which will be simple in construction, strong, durable, highly efficient and reliable in use, compact, light in weight, attractive in appearance and 15 which may be manufactured at low cost.

All of the foregoing and still further objects and advantages of the invention will become apparent from a study of the following specification, taken in connection with the accompanying drawings 20 wherein like characters of reference designate corresponding parts throughout the several views, and wherein:

Figure 1 is a view in front elevation of an indicator constructed in accordance with the present 25 invention.

Figure 2 is a front elevational view with the rotary disk removed.

Figure 3 is a view in vertical section, taken substantially on the line 3—3 of Figure 1.

30 Figure 4 is a view in horizontal section, taken substantially on the line 4—4 of Figure 1.

Figure 5 is a detail view in perspective of the rotary, resilient fingers and the hub therefor.

Figure 6 is a detail view in perspective of one of 35 the slidably shiftable members which coact with the fingers shown in Figure 5 for indicating rhythm.

Referring now to the drawings in detail, it will be seen that the embodiment of the invention 40 which has been illustrated comprises a casing 1 of suitable material, preferably metal, which is provided with supporting legs or similar supports 2. The casing 1 includes a removable front plate 3 which is secured in position, as at 4. The front legs of the casing 1 are integral with the plate 3.

Mounted horizontally in the casing 1 is a suitable support or bracket 5 upon which an electric motor 6 is mounted. The shaft 7 of the electric motor 6 projects rotatably through an opening 8 which is provided therefor in the plate 3 of the casing 1 and has fixed on its outer end portion a hub 9 having a reduced outer end portion upon which a disk 10 is fixed.

A bell 11 is mounted on the lower side of the support 5 for operative engagement by a hammer

12 which is mounted on the free end of a resilient arm 13 which, in turn, is secured at its other end to the plate 3, as at 14. The resilient arm 13 is formed or bent to provide a cam 15 which projects through a slot 16 which is provided therefor in the plate 3 rearwardly of the disk 10. Comparatively long and short resilient fingers 17 and 18, respectively, project from the hub 9, the finger 18 being engageable with the cam 15 when the electric motor 6 is in operation for forcing the hammer 12 away from the periphery of the bell 11 and suddenly releasing said hammer in a manner to permit the same to snap back to its former position for sounding the bell. The shaft 7 of the motor rotates in a clockwise direction and it will be noted that the shape of the cam 15 is such that the foregoing operation will be obtained. It will be noted that the resilient fingers 17 and 18 extend in parallel, abutting engagement with each other.

The plate 3 of the housing 1 is further provided with inner and outer radial slots 17x and 18x which are provided at predetermined places with respect to the cam 15. Radially shiftable abutments designated generally by the reference numeral 19 are slidably mounted in the pairs of radially aligned slots 17x and 18x. Each abutment 19 comprises a substantially flat spring 20 which is slidably mounted on the inner side of the plate 3, each spring 20 including an outwardly curved outer end portion 21 engaged with said plate 3. A threaded shank 22 projects from each spring 20 adjacent the curved end portion 21 thereof and is operable in the adjacent slot 18x. Nuts 23 are threaded on the shanks 22 and engaged with the outer side of the plate 3 for frictionally securing the abutments 19 in adjusted position. The curved end portions 21 of the springs 20 normally space those portions of said springs from which the shanks 22 project away from the plate 3 and it will thus be seen that when the nuts 23 are tightened, the springs 20 will be drawn toward the plate for providing a good frictional contact therewith. Shanks 24 project from the inner end portions of the springs 20 through the slots 17x and have fixed thereon flat, metallic lugs 25. When the abutments 19 are moved inwardly in the slots 17x and 18x, the lugs 25 will be in the path of the free end portion of the comparatively long resilient finger 17 for engagement thereby.

The reference numeral 26 designates a conductor wire which supplies electric current from any suitable source to the motor 6. Mounted in the housing 1 and interposed in the conductor 26 is a suitable speed control unit 27 which is ad- 110

justed through the medium of a hand crank 28 or the like which is provided on the front of the plate 3. If desired the unit 27 may be a combined switch and speed control device, or a suitable switch for controlling the flow of electric current to the motor 6 may be interposed in the circuit at any desired point.

An integral pointer 29 is provided on the periphery of the disk 10 for visually indicating the 10 beats about to be sounded and for indicating the position of the fingers 17 and 18. It will be noted that the pointer 29, when viewed from the front of the instrument, is aligned with the fingers 17 and 18, as seen in Figure 1 of the drawings. Any 15 suitable indicia or matter may be provided on the disk 10, such as charts of the various beat rhythms.

In operation, the motor 6 is energized to actuate the shaft 7 upon which the resilient fingers 20 17 and 18 and the disk 10 are fixed. With each complete revolution of the disk 10, the bell 11 is sounded by the engagement of the finger 18 with the cam 15, as previously explained, for giving the beat of the measure. For sounding substantially 25 any desired rhythm, the various abutments 19 are shifted inwardly to operative position to dispose the lugs 25 in the path of the projecting end portion of the comparatively long resilient finger 17. As the finger 17 engages each lug 25, 30 said finger 17 is flexed away from the finger 18 and suddenly released to strike the finger 18 for sounding the rhythm beat.

It is believed that the many advantages of a 35 musical time indicator constructed in accordance with the present invention will be readily understood, and although the preferred embodiment of the invention is as illustrated and described, it is to be understood that changes in the details of 40 construction and in the combination and arrangement of parts may be resorted to which will fall within the scope of the invention as claimed. For example, in lieu of the electric motor 6, a spring 45 motor or any other suitable means may be provided for actuating the device.

48 What is claimed is:—

1. A time and rhythm indicator comprising a 50 supporting structure, a shaft rotatably mounted on the supporting structure, means for rotating the shaft, audible signal means mounted on the shaft for rotation therewith, means mounted on the 55 supporting structure for operative engagement with the audible signal means for actuating the same, and an audible signal mounted on the supporting structure and operatively engageable by the first named audible signal means for actuation thereby.

2. A time and rhythm indicator comprising a

supporting structure, a shaft rotatably mounted on the supporting structure, means for rotating the shaft, a pair of comparatively long and short resilient fingers mounted on the shaft for rotation therewith in parallel, abutting engagement with each other, said fingers constituting an audible signal, and an abutment mounted on the supporting structure and operatively engageable with the comparatively long fingers for actuating the signal.

3. A time and rhythm indicator comprising a 80 supporting structure, a shaft rotatably mounted on the supporting structure, means for actuating the shaft, comparatively long and short resilient fingers mounted on the shaft for rotation therewith and extending in parallel, abutting engagement with each other, and a plurality of abutments shiftably mounted on the supporting structure for operative engagement with the comparatively long finger, said fingers constituting an 85 audible signal.

4. A time and rhythm indicator comprising a 90 housing, an electric motor mounted in the housing, a rotary shaft operatively connected to the electric motor, a bell mounted in the housing, a 95 resilient cam mounted on the housing, a hammer on the cam operatively engageable with the bell, comparatively long and short resilient fingers mounted on the shaft for rotation therewith, said fingers being in parallel abutting engagement 100 with each other and constituting an audible signal, one of the fingers being operatively engageable with the cam for actuating the hammer, and a plurality of abutments slidably mounted on the 105 housing for selective engagement with the comparatively long finger for actuating said audible signal.

5. A time and rhythm indicator comprising a 110 housing, an electric motor mounted in the housing, a rotary shaft operatively connected to the 115 motor, said shaft projecting outwardly from the housing, a disk fixed on the outer end portion of the shaft, a pointer on the disk, comparatively long and short resilient fingers fixed on the shaft 120 for rotation therewith and extending in parallel, abutting engagement with each other, said fingers, in conjunction with each other, constituting an audible signal, abutments mounted on the 125 housing and operatively engageable with the comparatively long finger for actuating the 130 audible signal, and a bell mounted in the housing and operatively engageable by at least one of the fingers for actuation thereby for sounding the bell upon the completion of each revolution of the shaft.
